UNITED STATES PATENT OFFICE.

WILLIAM F. DEISTER, OF FORT WAYNE, INDIANA.

SLIME-CONCENTRATOR.

1,010,350.

Specification of Letters Patent. Patented Nov. 28, 1911.

Application filed September 25, 1911. Serial No. 651,260.

To all whom it may concern:

Be it known that I, WILLIAM F. DEISTER, residing at Fort Wayne, in the county of Allen and State of Indiana, a citizen of the United States, have invented or discovered certain new and useful Improvements in Slime-Concentrators, of which improvement the following is a specification.

The invention described herein relates to certain improvements in slime concentrators, and has for its object a construction and combination of elements whereby the shifting of the table from feed to washing position and back to feed position, is effected automatically.

It is also an object of the invention to provide for the automatic movement of the table in accordance with the richness of the material treated.

20 A further object of the invention is the utilization of the water employed in shifting the table, to remove the values, etc. deposited thereon.

25 The invention is hereinafter more fully described and claimed.

In the accompanying drawings forming a part of this specification Figures 1 and 2 are side elevations of a slime concentrator embodying my improvements, Fig. 1 showing the apparatus in feed position and Fig. 2 showing the same in washing position; Fig. 3 is a top plan view; Figs. 4 and 5 are views similar to Fig. 1 illustrating modifications in the table shifting means and Fig. 35 6 is a side elevation illustrating a further modification of my improvement.

In the practice of my invention it is preferred to employ tables, each of which preferably consists of a series of decks 2, constructed and pivotally mounted as described and claimed in an application Serial No. 632,743 filed by me June 12, 1911. As set forth in said application the several decks are pivotally supported about midway of their length on shafts 5 which are mounted on posts or columns 6. The decks forming a table are connected so as to move in unison by straps 8 arranged adjacent to the ends of the decks. Suitable means as boxes 12 having fan shaped directing trays 13 are arranged at one end of the table for feeding the material onto the decks, which when in feed position incline downwardly at a suitable angle from the trays. Pipes 17 having perforations or nozzles are arranged across the ends of the decks in suitable relation

to the upper surfaces thereof to effect a washing off of deposits. These pipes are connected by flexible tubes 19 to a water supply pipe 20 provided with a controlling valve 21, adapted to be opened and closed as the table moves to and from washing position, as fully set forth in the application referred to. In the form of apparatus described and shown in said application the table is shifted from feeding position to washing position and back to feeding position by a motor driven mechanism and consequently without any regard to the richness of the materials treated. In order to avoid the use of such motor driven mechanism, the first cost of which is considerable as is also the cost of operation and maintenance, a natural force as gravity is employed for effecting the desired movements of the table.

In the construction shown in Figs. 1, 2 and 3 one or more tanks or receptacles 35 are secured to the table at one side of the pivotal point and preferably closely adjacent to one end, thereby permitting of the employment of comparatively small tanks. The table should be so constructed and mounted that the end opposite that onto which the material is fed, will have a considerable preponderance of weight in order that the table may be held in feed position a sufficient length of time for the separation of the values. Suitable means are provided for discharging a liquid as water into the tank or receptacle. In the construction shown the tank 35 is connected by a flexible pipe 36 to a storage tank 37 secured at a suitable height to the post 6. For charging this tank a branch pipe 38 is attached to the pipe 20 for supplying the washing water. The flow of water to the tank or receptacle 35 is regulated by a valve 39 in the branch pipe. This valve during the discharge of liquid from the counter-balancing tank 35, may be automatically closed and to this end an arm 40 is secured to the stem of the valve 39 and is also connected by a link 41 to the table. This connection is so constructed that the valve will be closed while the table is in washing position and opened during the feed of material onto the table. As soon as sufficient weight in the form of liquid and deposited values have been placed on the feed end of the table, to overcome the normal bias of the table the latter will turn on its pivotal supports to an opposite and

sharper inclination as shown in Fig. 2. As it reaches washing position the stem of valve 42 strikes a suitable abutment and the valve is shifted against the tension of its closing spring to open position, thereby permitting of the escape of the counter-balancing liquid from the tank 35. As the table moves to washing position the valve 21 is opened permitting the discharge of water along the upper surfaces of the table and the consequent removal of deposits into the launder 33. As soon as the deposits are removed and a sufficient quantity of liquid has escaped from the tank 35, the normal preponderance of weight of the portion of the table opposite that carrying the tank, will cause a return of the table to feed position, whereupon the valve 39 will be opened and the liquid will again flow into the counter-balancing tank.

In order to prevent shocks or jars to the table when shifted, resilient checks are provided. These cushioning devices can be made in any suitable manner, as for example that shown consisting of spring jaws 43 and blocks 44 having a width greater than that between the jaws. It is preferred to attach the blocks to the table and the jaws to a suitable support as shown, although this arrangement may be reversed. If desired the blocks may be reduced in width a short distance back of their ends so that the jaws will have a grip thereon and prevent any movement of the tables for a short time (proportional to the grip) after the liquid has been charged into or discharged from the tank in sufficient amount to cause or permit a movement of the table.

In treating materials the largest percentage of values will be deposited on the surfaces adjacent to the feed end, and by properly adjusting the flow of water into the tank 35, the shifting of the table to washing position may be made dependent on the richness of the material being treated. The richer the material the more rapid the accumulation of sufficient values to supplement the added weight of liquid and effect a shifting of the table from feed position. If the material is less rich in values the accumulation of the latter on the decks will be rich in values, and hence, the flow of liquid to the tank being the same, a longer time will be required to cause a shifting of the table.

As shown in Fig. 6 the table may be pivotally supported at one end, it being preferred that the decks 2^a forming the table should be as described and claimed in an application Serial No. 633,171, filed June 14, 1911. In this form of table which is pivotally supported at one end the counter-balancing tanks 35^a are so connected to the free end of the table that when charged they

and thereby bring the table to feed position. During such feed the liquid will be discharged from the tanks until such time that the weight of the tables plus the accumulated deposits thereon will become sufficient to overcome the weight of the opposite end of the table. During the flushing period the tanks will be charged with liquid. A convenient construction for the automatic shifting of the table consists in connecting the tanks to ropes 24 passing over guide pulleys 26 and having their opposite ends attached to the table. As in this construction the tanks will be charged during the flushing period, the pipe 38 for filling the tanks is preferably connected to the flushing supply pipe 20 below its controlling valve 21 which is opened and closed by the table when shifted. In Fig. 6 the table is shown in feed position and the tank dropped to a point where its discharge valve is opened. As soon as such an amount of water has escaped from the tank that the weight of the free end of the table and accumulated values will overbalance the weight of the tank the table will move to washing position and in its movement open valve 21 permitting water to flow along the table and also to flow into the tank. As soon as sufficient water has entered the tank the latter will move down shifting the table to feed position.

As shown in Figs. 4 and 5 the liquid discharged from the counter-balancing tanks may be employed in flushing the table. In Fig. 4 the counter-balancing tank is carried by a lever 46 having its opposite end connected to the table. A trough or launder is arranged in the line of movement of the tank, and in such relation to its range of movement, that when the table reaches feed position the discharge valve of the tank will be opened, permitting the liquid to flow into the launder and thence into the reservoir 48 which is connected to flushing supply 20. The flow of liquid from this reservoir to wash the table is controlled by a valve 21 shiftable by the table as heretofore stated.

As will be readily understood by those skilled in the art, the counter-balancing tank may be connected to the table by a rope 49 which may be passed over one or more guide pulleys 50, thus permitting of the tank being arranged at a considerable distance from the table as shown in Fig. 5. And further the counter-balancing tank and the reservoir may be arranged one directly above the other, the discharge valve of the tank being shifted to open position by an abutment 51 on the reservoir. As the water employed for shifting the table may not be sufficient to effect a thorough washing off of the table, an additional quantity may be supplied by a pipe 52, the flow of water into the reservoir being controlled by a float valve 53.

It is characteristic of my improvement that after the valves controlling the flow of liquid into and from the counter-balancing tanks have been properly adjusted and the apparatus set into operation, that its operation is entirely automatic and will continue practically without attention, whether material is being fed into it or not. It is also characteristic of my improvement that after the apparatus has been put into operation, the feeding periods will be automatically varied in accordance with the richness of the materials fed to the table.

I claim herein as my invention:

- 15 1. In a slime concentrator the combination of means for feeding slime, a concentrating table normally inclined downwardly from the feed end, adapted for automatic movement from normal position with automatically variable gravity operated means for restoring the table to the normal position.
- 20 2. In a slime concentrator the combination of means for feeding the slime, a pivotally supported concentrating table weighted to normally maintain concentrating position and automatic and incrementally varying means for shifting it from and returning it to concentrating position.
- 25 3. In a slime concentrator the combination of pivotally supported concentrating table, incrementally varying gravity operated means for shifting the table in one direction, and automatically and incrementally varying means for shifting the table in the opposite direction.
- 30 4. In a slime concentrator the combination of a pivotally supported concentrating table weighted to be maintained normally in one position, automatically and incrementally varying means for shifting the table from normal position, and incrementally varying means controlling the return of the table to normal position.
- 35 5. In a slime concentrator the combination of a concentrating table normally inclined and having a bias to move in one direction, a tank adapted when charged with liquid to move the table in the opposite direction, and automatic means for alternately charging and discharging the tank during

concentrating and concentrates discharging periods.

6. In a slime concentrator, the combination of a concentrating table normally inclined and having a bias to move in one direction, automatically variable gravity operated means for shifting the table in the opposite direction and automatic means for varying the periodicity of the movement of the table according to the richness of the material being treated.

7. In a slime concentrator the combination of a concentrating table, means for feeding material onto one end, means for washing the table, said table having a bias to move in one direction, gravity operated means for shifting the table in the opposite direction, and automatic means controlling the periodicity of the movement of the table to washing position according to the richness of the material being treated.

8. In a slime concentrator, the combination of a concentrating table, means for feeding material onto the table, means for discharging water along the table, said table having a bias to move in one direction, a tank adapted when charged to move the table in the opposite direction, means for charging and discharging the tank, and means for conducting the discharge water to wash directing means.

9. In a slime concentrator the combination of a concentrating table, gravity operated means for shifting the table in one direction, gravity operated means for moving the table in the opposite direction, and automatic means for delaying the movements of the table.

10. In a slime concentrator the combination of a concentrating table, means for feeding material onto the table, means for washing the table, automatic means for shifting the table to and from feeding and washing positions, and automatic means for delaying the movements of the table.

In testimony whereof, I have hereunto set my hand.

WILLIAM F. DEISTER.
